UNITED STATES PATENT OFFICE.

CYRUS CHAMBERS, JR., OF PHILADELPHIA, PENNSYLVANIA.

BRICK-MACHINE.

SPECIFICATION forming part of Letters Patent No. 297,917, dated April 29, 1884.

Application filed December 29, 1883. (No model.)

To all whom it may concern:

Be it known that I, CYRUS CHAMBERS, Jr., a citizen of the United States, residing in the city and county of Philadelphia, and State of Pennsylvania, have invented certain new and useful Improvements in Brick-Machines, of which the following is a full, clear, and exact description, reference being had to the accompanying drawings.

10 This invention embodies improvements in certain details of the brick-making machines long well known as the "Chambers Brick-Machines," and patented to me in various Letters Patent of the United States—as, for example, in my Letters Patent No. 207,343, of August 27, 1878, and No. 275,467, of April 10, 1883, and others previous thereto; also in a machine of the same general class, with wire cut-off mechanism, radically different from any mechanism for a like purpose known to me, for which I filed an application for Letters Patent of the United States on the 8th day of February, 1883, which application was allowed on the 5th day of November, 1883.

25 Of the drawings hereto annexed, and forming a part of this specification, Figure 1 is a general elevation of the entire machine provided with my improvements, the front side of the tempering-case I C being broken away. Fig. 2, Sheet 2, is a plan view of the cross-head and thrust-plates at the rear end of the pugging or knife shaft S enlarged. Fig. 3 is a vertical longitudinal section, partly in view, as on the line a a, Fig. 2. Fig. 4 is a rear end 35 view of the pugging-shaft. Fig. 5 is a front end view of the thrust-plate which fits on the end of said shaft. Fig. 6 is a rear end or face view of the plate, Fig. 5. Fig. 7 is a longitudinal section through the thrust-plate and shaft as taken on the line a b, Fig. 5. Fig. 8 is a similar section, as on line a c, Fig. 5, with the plate also fitted on the end of the shaft, as in said Fig. 7. Fig. 9, Sheet 3, is a rear view of the screw-case S C, Fig. 1, detached, showing its adjustable lining and mode of securing the same in the different positions. Fig. 10 is a view of the front face of the screw-case. Fig. 11 is a front face view of the die-case D C detached from the screw-case. Fig. 12 is a 45 longitudinal horizontal section, as on line a a, Fig. 10, of the die-case and screw-case con-

nected. Fig. 13, Sheet 4, is a side elevation, enlarged, of the friction-belt mechanism for conveying certain auxiliary movement to the propulsion-belt P B. Fig. 14 is a plan view 55 of detail of the pivoted lever L L', Fig. 13. Fig. 15 is a detail of cut-off-belt plates D, Figs. 1, 17, and 18, to which the wire-holding U-shaped bows are secured. Fig. 16 is a detail showing the improved form and the arrangement of the independent roller I, Figs. 1 and 13. Fig. 17, Sheet 5, is a side view of part of the cut-off mechanism, partly in longitudinal section. Fig. 18 is a transverse sectional view, looking in the direction of the adjacent arrow, as on the line a a, Fig. 17, showing the construction of the forward cut-off-belt pulley, scraper, and wings, and the guide-ways for the belt-plates D, the parts not necessary for the purpose not being shown in the figure. Fig. 19 is a front view of the inlet-pipe in relation to the tempering-case and knives. Fig. 20, Sheet 6, is a transverse section of the off-bearing frame and belt, as on line c c, Fig. 1. Fig. 21 is a side elevation of 75 part of the off-bearing-belt frame, the cap-piece thereof being cut off, as on line d e, Fig. 20. Fig. 22 is a plan view of one of the adjustable bearing-strips z, Figs. 20 and 21, detached, in which the off-bearing-belt rollers 80 are journaled.

The same letters mark the same parts where they occur.

The devices illustrated on Sheets 1, 2, and 3, and in Fig. 19, Sheet 5, concern parts connected with the clay tempering and expressing mechanism. Those on Sheets 4 and 5 (save said Fig. 19) relate to improvements in the wire cut-off mechanism and adjuncts, which mechanism was the subject of my aforesaid allowed application for a patent. Those on Sheet 6 relate to the off-bearing-belt frame.

The main object of the present improvements, which I shall now proceed to set forth in detail, is to remedy certain defects that experience has shown existed in my previous brick-machines.

First. The first of these relates to a modification of the means described in my Patent No. 207,343, of August 27, 1878, of fitting the thrust-plate onto the end of the pugging-shaft, whereby such fitting is facilitated.

Referring to the general elevation of the machine, Fig. 1, and more particularly to the enlarged detail drawings on Sheet 2, A marks the pugging-shaft, to which the tempering knives *k* and the expressing-screw *S'* are attached. The rear end of this shaft has a shoulder, *b*, and longitudinal indentations *b'*—four in the present instance. The socketed thrust-plate *b²*, whose rear face is a true plane surface having the usual oil-conveying grooves, *b³*, is provided with internal lugs, *b⁴*, corresponding to the indentations in the end of the shaft, so that when the said plate is applied to the latter its lugs will enter the indentations in the shaft until the face of the offset *b⁵* in the front of the socket of the plate bears against the shoulder *b*. The extreme end of the shaft should not touch the bottom of the socket, so that the only bearing-surfaces shall be those of the shoulder and the offset. By this construction the thrust-plate *b²* is not only obliged to rotate with the shaft, but the fitting of the former to the latter, in order to insure the true running of the plate, is greatly facilitated, as it is merely necessary to true up in the lathe the contiguous faces of the shoulder and the offset.

In order that the purpose of the foregoing-described construction may be further understood, I shall explain briefly the parts with which the said plate is immediately connected.

At the rear end of the main frame of the machine is a cross-head, *b⁶*, attached to the frame by bolts *b⁷*, and having a cavity therein for the reception of the rear end of shaft A and the thrust-plates. This cavity also forms an oil-chamber, *b⁸*. Its rear side is concave, to receive the convex rearward projection of a loose thrust-plate, *b⁹*, which is prevented from turning by a vertical lug, *b¹⁰*, that enters a groove in the rear of the box. By means of the nuts *b¹¹* on bolts *b⁷* the cross-head may be adjusted longitudinally as occasion may require, and consequently the pugging-shaft and its appendages, together with the thrust-plates as a whole.

Second. The next improvement relates to the detachable ribbed lining R, Sheet 3, of the screw-case S C; and it consists in adapting the same, so that it may be shifted around and secured so as to present a new surface underneath the expressing-screw *S'*, Fig. 1, when the surface which has been in use has become worn away by reason of the friction and consequent wear from the attrition of the clay being obviously greater on the lower side. To accomplish this, I provide the rear edge of the said movable lining with suitable slots, *r²*, for the reception of fastening-lugs *r³*, which are secured to the end of the screw-case by bolts *r⁴*, Figs. 8 and 9. When it is required to alter the relative position of the lining, said bolts are unscrewed, when the lining may be rotated until the two other opposite slots are brought into coincidence with the lugs *r³*, respectively, which are then bolted in place.

Third. The next improvement relates to the form of the lower end of the pipe M, through which the clay is delivered into the tempering-case, Figs. 1 and 19. The circle described by the free ends of the knives *k* being designately usually four to six inches less in diameter than that of the inner side of the case T C, there is always left within the latter a fixed shell or lining of clay. (Indicated by the broken-line circle *x*, Fig. 19.) Heretofore this clay lining would gradually build itself up across the mouth of the inlet-pipe, and thus form an obstruction to the discharge of the clay into the case. This clay barrier had, therefore, to be broken away from time to time by means of a pole thrust down the pipe. I now obviate this difficulty by extending the lower extremity of the latter down into the tempering-case, close to the sweep of the subjacent knives, 85 and give to it the curvilinear form shown in Figs. 1 and 19—more clearly in the latter figure. I have sometimes struck this curve upon the same radius as that of the circle made by the rotating knives; but I prefer to cut off the 90 end of the pipe on the side first reached by the knives in their rotation, as shown in Fig. 19. The object of this preference is to prevent the breaking of the pipe by means of a large stone that, if the end of the pipe projected too far down on that side, might be jammed against the latter by the knives. Besides, the lining of clay is not apt to build itself up from that side.

By the construction described, it will be obvious that the clay lining is cut off from extending itself up beyond the projecting curved end of the inlet-pipe, and thus a heretofore annoyance is escaped.

Fourth. The next improvement consists in providing the die-case D C with lateral lugs L on that side next to the pivoted eye or lock bolt *e*, for the purpose of affording a suitable purchase or fulcrum for a bar, *y*, to aid in swinging open the die-case. (See figures on Sheet 3.) 105

That the nature of this improvement may be clearly apprehended, I shall explain that heretofore, owing to the elasticity of the clay packed in the screw and die cases, it was necessary, in order to free the eyebolt *e* before it 115 could be swung out from the eye *e'* of the die-case, preparatory to opening the latter, to unscrew the nut *e²* on the end of said bolt a considerable distance, and thereby considerable time was lost when it was required to open out 120 the die-case in order to remove an obstruction lodged therein or for other purpose. I now insert the bar *y*, Fig. 11, between the upper one of the lugs L and the end of the bolt *e*, first having slightly loosened the nut *e²*, and 125 by pressing against the bar the bolt is forced outward a certain distance. I then drop the bar down between the bolt and the lugs in the position indicated by the broken lines in Fig. 11, the bolt having been forced out from the 130 eye a sufficient distance by the first operation described to allow this to be done. I then ma-

nipulate the bar against the fulcrum-lugs, and thus cause the bolt to clear the eye e' , whereupon the die-case may readily be swung open on its hinge h .

5 The foregoing-described features relate to parts of the machine connected with the tempering and expressing mechanism. Those improvements now to be set forth relate, mainly, to the wire cut-off mechanism and adjuncts 10 described in my aforesaid application for a patent, which was filed on the 8th of February, 1883; and in order that these recent improvements may be fully understood and in their proper relations, I shall first explain the 15 general construction and operation of said cut-off mechanism.

Referring, primarily, to Fig. 1 of the annexed drawings, the clay that is forced out through the die D' of the machine in a continuous 20 bar (indicated by the broken lines C , Fig. 1) by the devices therein shown, or other suitable mechanism, is delivered upon an endless belt, $P B$, herein, and in said previous application termed the "propulsion-belt." This belt runs 25 over pulleys P and P' and a series of rollers journaled in a horizontal frame, F . By reason of the friction of the advancing bar of clay upon belt $P B$ motion is imparted to the latter, which in turn sets in motion the cut-off 30 devices, as will hereinafter appear. The cut-off mechanism consists of a series of equidistant transverse wires, $c w$, stretched at distances apart equal to the length of the bricks to be severed from the clay bar upon elastic U -shaped bows U , attached to long flat plates D , in the manner shown, that are in turn mounted 35 upon an endless belt, $C B$, termed the "cut-off belt," immediately over and above the path of the bar of clay. This belt runs over 40 pulleys P'' and P''' , journaled in a vertically-adjustable frame, F' , and they are arranged and adjusted, as shown, so that the lever side of the belt is inclined toward the propulsion-belt, dipping in the direction of motion of the 45 latter, and consequently of the bar of clay. The shaft s' of pulley P' , over which belt $P B$ runs, has a pinion, W , whose teeth engage with those of a spur-gear, W' , that is carried by the shaft s'' of pulley P'' , over which runs the 50 cut-off belt, so that the motion given by the bar of clay to the propulsion-belt rotates said pinion, gear, and pulley, thereby moving the cut-off belt in the direction of the arrow adjacent thereto, and thus the wires $c w$ are caused 55 successively and gradually to enter the bar of clay, and to move along with it and diagonally across its path, yet finally severing the bar at right angles into bricks $b r$. The end of the bar of clay is received upon an independent 60 roller, I , in line horizontally with the upper surface of the propulsion-belt. From this roller the severed brick is received by and upon the off-bearing belt $O B$, running over a system of pulleys, P^2 , P^3 , P^6 , and P' , which belt is in line a little below the top of the 65 roller I , and is caused to move at a more rapid

speed than the propulsion-belt, so as to separate the bricks for convenience of handling by the off-bearers.

The preceding description, with the assistance of the drawings hereunto annexed, will give a good general idea of the construction and *modus operandi* of the apparatus, sufficient for the full comprehension of the special improvements I am about to describe. 70

Fifth. The first of these (fifth in the order of enumeration I have adopted herein) relates to the vertical adjustment of that portion of the propulsion-belt frame F to the rear of the vertically-adjustable cut-off frame F' . The 80 object of such adjustment of frame F is that it may be brought to the proper height so as to insure the propulsion-belt being in line with the bottom of the die of the machine—that is to say, in line with the underside of the bar of clay 85 as it issues from the die. I accomplish this purpose by means of vertical screw-bolts a , Fig. 1, passing through lateral flanges a' in the supporting-legs a'' of the frame. As the bolts are turned, so is the superincumbent frame raised 90 or lowered. As, owing to the flexibility of the bar of clay, and the very little adjustments required, it is unnecessary that the entire belt-frame should be moved, its end, next the cut-off frame, and which end rests upon a rear 95 projection, a'' , of the latter, is pivoted on a through-bolt, a'' .

Sixth. The next improvement to be described is one of considerable importance to the successful operation of the cut-off under varying 100 conditions. In describing the same, I shall refer to Figs. 1, 17, and 18; especially to the last figure. It is well that I should first explain that in the machine which was the subject of my said allowed application for a patent the 105 upward strain of the cut-off belt occasioned by the resistance offered by the clay to the passage through it of the cut-off wires was taken by a line of small rollers journaled closely together transversely in the inclined 110 cross-pieces g of the "cut-off frame" F' , as I have termed it. The defect in that construction, as I soon discovered, was that the cut-off was marred, especially in very stony or gritty clays, by reason of the trembling or wabbling 115 of the cut-off-wire supports and of the cut-off belt, as there was no lateral or underneath support of the belt, or rather of the plates D , to which the wire-retaining U -shaped bows were secured. The present improvement is 120 intended to, and does, in fact, to a great degree, remedy this defect. This I do by making the plates D wider than the cut-off belt, and providing, in lieu of the said line of rollers, lateral guideways G on each side of the frame F' in 125 the cross-pieces g , in which ways the side extensions of the plates D beyond the edge of the cut-off belt enter and are permitted to slide freely but closely therein, as seen most clearly in Fig. 18. The detachable bottom 130 pieces or strips, G' , of said guideways are secured to the bars g , whose underneath surfaces

form the upper bearings of the plates D, by means of screws g^2 .

Seventh. Before entering upon a description of the important improvement now to be set forth, I shall explain that in the apparatus which was the subject of my said application filed February 8, 1883, I relied wholly upon the moving bar of clay, in connection with the propulsion-belt and the intermediate gearing, to propel the cut-off belt. I found, however, upon observing the operation of the devices with various kinds and consistencies of clay, that this was not reliable under all circumstances. When the clay was in proper condition, it worked admirably; but when the clay became soft, and consequently issued from the die of the machine with increased speed, and not having sufficient strength to propel the cut-off mechanism and cause it to respond to the acceleration, the bar would upset or "buckle-up," and thus seriously interfere with the operation of the cut-off. In order to remedy this defect, I provide a device whose function is to convey a certain amount of power to the propulsion-belt, auxiliary to that of the moving bar of clay, sufficient to relieve the latter from doing more of the work of propelling the cut-off mechanism than may, under any condition, of the clay, be beyond its strength.

In describing this device, which I shall term the "compensator," I shall refer to the general elevation of the machine, Fig. 1, and to the enlarged detail, Fig. 13, Sheet 4. The shaft s^1 of the forward propulsion-belt pulley, P' , is extended beyond the frame in which it is journaled, and is provided with a flanged pulley, P^8 , while a like extension of the shaft s^2 of the bevel-gear b^g , Fig. 1, has in line with pulley P^8 a pulley, P^9 , also preferably flanged on each side, (although not so shown,) so as to retain the slack friction-belt $F\ B$ in place. This belt runs over both of said pulleys, and also over an idler-roller, $I\ R$, that is journaled at the forward end, L , of a lever, $L\ L'$, which is secured to a stud, f^3 , pivoted to a bracket, f , of the post f^2 , which supports the cut-off mechanism, &c. This lever bears on its other arm, L' , a weight, w , which is adjustable on the latter, and is held at any desired point by means of a thumb-screw, f^5 .

Referring to Fig. 1, the shaft s^2 of pulley P^9 , which shaft, I may state in passing, also carries the pulley P^{10} , Fig. 1, that drives the off-bearing belt $O\ B$, is rotated from the main gearing of the machine through a shaft, s^4 , and bevel-gears b^g and b^g' ; and the relative diameters of the pulleys are such that the propulsion-belt may be driven at as great or greater speed than that at which the bar of clay may issue from the die, through the medium of the friction-belt connection. Now, it is manifest that as the pressure of the idler against the belt $F\ B$ is increased or diminished, according to the position of the weight w upon the rear arm of the lever, a corresponding speed is lent to the propulsion-belt. The weight

having been adjusted to suit the general character of the particular clay being worked, so that a sufficient compensatory power is conveyed to the belt $P\ B$ for the purpose recited, 70 usually very little change in the adjustment is necessary.

I have referred to $L\ L'$ as a single lever, which it is in effect. It is, however, preferably, though not essentially, a combination of two independent arms, one of which, L' , (see Figs. 13 and 14,) is keyed to the stud f^3 , and the other, L , is rotatable thereon, and is secured in any desired position by a set-screw, f^6 . The meaning of this construction is to 80 provide a means for keeping the arm L always in a horizontal position, while the idler may be adjusted up or down, so as to suit the length of the belt $F\ B$, which becomes slack from use. I have also added a pulley, $P\ P$, 85 Figs. 1 and 13, which is journaled underneath the propulsion-belt frame adjacent to the pulley I' , over which pulley $P\ P$ the propulsion-belt is carried, whereby the latter is caused to hug the pulley I' around some two-thirds 90 of its periphery, thus obviating the heretofore tendency of the belt to slip upon the latter.

Eighth. The next improvement relates to the belt-plates D, to which the U-shaped elastic bows U are secured; and it consists in providing said plates at each end thereof with upturned flanges d^1 , Figs. 1, 15, 17, and 18, between the margins of the plates which slide in the guideways G. These flanges serve also to stiffen the plates; but their principal purpose is to retain the droppings of clay from the cut-off wires until the plates turn over the smaller pulley P^4 , and which droppings might otherwise fall down upon the cut-off belt and get underneath plates D, thus preventing them 100 from finding their proper bearing upon the surface of the belt.

Ninth. The next improvement has relation merely to the independent roller I, which, as before stated, receives upon it the end of the bar of clay; and it consists in giving the same a tapering form toward each end, as illustrated in Fig. 16. This roller is struck by the cut-off wires successively as they begin to turn up over the large pulley P^3 , after having finally 115 severed the bar of clay. Heretofore I have made the same quite cylindrical in form; but I discovered that the cut-off wires, owing to frequent bending over the roller and the sharply-defined or square edges thereof, would become weakened, and after a time break. By making this roller tapering, as shown, it is adapted to the natural or even curve of the wires.

Tenth. The next improvement concerns the 125 construction of the scraper S and its connections, which I use to clear the face of the cut-off-belt pulley P^3 of any clay that may chance to drop upon and adhere to the same. The improvement consists in making the inclined 130 wings H (whose office is to deflect the clay removed from the pulley by the scraper, so that

it will fall beyond the machine) a fixed part of the frame F' of the cut-off mechanism, and mounting the scraper thereon adjustably, instead of making the scraper and wings in a single piece, as heretofore. The scraper is constructed in the form of a saddle, as shown in Fig. 18, and is straddled over the apex of the wings H, and is secured in position by means of a screw, t', in a slot, t'', whereby the scraper may be also properly adjusted against the face of the pulley P'.

Eleventh. The next improvement—one of minor importance—relates to a certain construction whereby the sliding frame T, Figs. 15 1 and 17, that carries the small pulley P' of the cut-off belt, is made more conveniently adjustable when it is desired to increase or diminish the distance of that pulley from its fellow P', as the cut-off belt is lengthened or shortened, loosened or tightened. In my said allowed application for a patent, this frame T was thus adjustable by means of a headed screw-bolt passed through a cross-bar at or near the rear end of the frame, and also through 25 another fixed cross-bar of a rearward extension of the cut-off frame F'; and the pulley-frame was tightened up by means of a nut working on the threaded portion of said screw-bolt, against the outside of the last-mentioned cross-bar. I have now reversed the pulley-frame T, as seen most clearly in Fig. 17, so that its cross-bar T' extends to the front instead of to the rear of its pulley P', as before; and as a means for adjusting the frame longitudinally, for the purpose described, I employ a threaded bolt, t', working in a corresponding hole in the cross-bar T'. The forward end of this bolt impinges against the bottom of a socket, t'', in a downward projection, T', Figs. 17 and 18, from the fixed scraper-wings H. Bolt t' has a fixed nut, t'', thereon, and a jam-nut, t', Fig. 17. To make the required adjustments of the pulley and frame, it is obvious that it is merely requisite to apply a wrench to the nut t'', first 40 loosening the jam-nut, if necessary, when the bolt may be turned as desired, merely forcing out the frame T or permitting it to be drawn in, as the case may be.

Twelfth. The twelfth and last of the present 50 improvements relates to the off-bearing frame O F, and is illustrated by the Figs. 20, 21, and 22, Sheet 6: Reference may be also had to Fig. 1. It consists in certain details of construction that I will proceed to describe. 55 The rollers r', which sustain the off-bearing belt O B, are journaled in strips z, of preferably yellow pine, on each side of the frame. I now make said bearing-strips adjustable longitudinally, in order that new slots therein 60 for the shafts of the rollers may be shifted in lieu of the old ones when the latter became worn away, but more especially in order that the roller-shafts may be readily adjusted, so that they will always be at right angles to the path of the off-bearing belt. I do this by means of slots v and bolts v', as shown in the

plan view, Fig. 22, and as indicated by the broken lines in Fig. 21. I also make the roller-shafts long enough to nearly touch bracket or corner pieces z on each side of the frame, so that there may be no lateral movement of the rollers, and consequently of the belt. I make the top or cap pieces, z', a little above the line of the upper surface of the belt, and project the same inwardly beyond the line of the bearing-strips z, close to the ends of the rollers r'.

The object of the described construction is twofold. In the first place, it facilitates the operation of "edging" the bricks by the off-bearers—that is, the turning of them over side or edge wise upon the cap-boards z', from the off-bearing belt—for greater convenience of handling in loading upon the wheel-barrows or cars. The inner edge of caps z' being close to the belt, and their top surfaces elevated slightly above the belt, the bricks are readily "edged" over upon the former, out of the way of the moving belt and bricks carried thereby, as shown in the transverse sectional view of the off-bearing frame, Fig. 20, in which b r' marks the next coming brick, and b r'' the one just edged. The caps z' projecting over and beyond the bearing-strips z, near to the ends of the rollers, any sand or dirt that may fall from the bricks or the belt over the latter is prevented from getting into the bearings of the rollers.

Having thus described my invention, those features which I claim as new, and desire to secure by Letters Patent, are as follows:

1. The improvement in the means for fitting the socketed thrust-plate onto the end of the pugging-shaft, consisting in providing the latter with a shoulder and longitudinal indentations, and said thrust-plate with a corresponding bearing or shoulder, and internal lugs adapted to register with and enter said indentations in the shaft, the bearing-surfaces being trued up, all substantially as and for the purposes specified.

2. The screw-ease lining adapted to be rotated to different positions with relation to the ease and the expressing-screw, and provided with means, substantially as shown, for securing the same in such different positions, substantially as and for the purpose described.

3. The combination of the screw-case, the rotatable lining having the slots r'', and the fastening-lugs r', substantially as and for the purpose specified.

4. The inlet-pipe having its lower extremity extended into the tempering-ease beyond the inside periphery thereof, in proximity to the circle described by the subjacent knives, and of curvilinear form, substantially as shown, and for the purpose set forth.

5. In combination with the screw-case and the pivoted eye or lock bolt, the hinged die-case provided with the fulcrum-lugs L, arranged with relation to the eyebolt as and for the purpose specified.

6. In combination with clay expressing and molding devices, the propulsion-belt and cut-off mechanism, and frame F, with means, substantially as shown, for adjusting the said frame vertically, for the purpose specified. 55
7. The endless cut-off belt or carrier having plates D secured thereto, the guideways G, substantially as and for the purpose set forth. 60
8. The endless cut-off belt or carrier, the plates D, with their sides extending beyond the edges of said belt, the bows U and cut-off wires mounted thereon, and the guideways G, all constructed, combined, and adapted to operate substantially as and for the purposes stated. 65
9. The clay-expressing mechanism, the propulsion-belt, the cut-off mechanism consisting of a series of wires mounted transversely upon an endless belt or carrier, arranged with relation to the propulsion-belt and the moving bar of clay thereon, substantially as shown, and adjustable frictional devices, substantially as shown, for conveying auxiliary motion to said propulsion-belt, all combined, constructed, and operating substantially as and for the purposes set forth. 70
10. The following elements in combination, to wit: clay-expressing devices, an endless belt running over pulleys journaled in a frame, and adapted to receive thereupon the bar of clay issuing from the die of the machine, a pulley, as P⁴, on the shaft of the forward one of said pulleys, a positively-driven pulley, as P⁵, an idler, as I.R, on a pivoted adjustably-weighted lever, as L.L', a slack or friction belt running over said last-mentioned pulleys and in contact with said idler, together with mechanism for severing the moving bar of clay into bricks, consisting of a series of wires mounted on an endless belt or carrier, arranged with relation to the propulsion-belt and the bar of clay thereon, as shown, all constructed and adapted to operate and co-operate substantially in the manner and for the purposes set forth. 75
11. The combination of the propulsion-belt, the cut-off mechanism, the pulleys P⁸ and P⁹, the idler I.R, the friction-belt, and the weighted pivoted lever L.L', composed of two independ- 80
- ent arms adjustable with relation to each other, substantially as and for the purpose described. 85
12. In combination with the endless wire cut-off belt or carrier, the plates D, when provided with the upturned flanges d', substantially as and for the purposes specified. 90
13. In combination with the propulsion-belt and cut-off mechanism, the independent roller I, having the tapering form shown, and for the purpose specified. 95
14. In combination with the pulley P³ and the deflecting-wings H, the detachable scraper S, adjustably mounted on the latter, substantially as and for the purpose specified. 100
15. The combination, with the cut-off belt running over pulleys P³ and P⁴, mounted in the frame F', of the tightener-frame having the pulley P⁴ journaled therein, and the adjusting-screw t', working in said tightener-frame, and having its forward end abutting against a projection, T', located between said pulleys P³ and P⁴, as and for the purpose specified. 105
16. In combination with the off-bearing belt and its frame and rollers, the cap-pieces z², in proximity to the edges of said belt and rollers, and having their top surfaces elevated slightly above the belt, as and for the purposes specified. 110
17. In combination with the off-bearing-belt rollers, the cap-pieces z², covering the journals of the rollers, and extending over near to the ends of the latter and beyond the bearings thereof, as and for the purpose specified. 115
18. The combination, with the off-bearing-belt rollers, of the cap-pieces z² and corner-pieces z', the ends of the journals of said rollers being nearly in contact with said corner-pieces. 120
19. The combination, with the rollers r', of the longitudinally-adjustable bearing-strips z, cap-pieces z², and corner-pieces z', constructed and arranged as specified. 125
- In testimony whereof I have hereunto affixed my signature this 18th day of December, A. D. 1883.
